PREFABRICATED HOUSING

Edwin Bird Wilson, Forest Hills, N. Y.

Application October 29, 1938, Serial No. 237,639

8 Claims. (Cl. 189—1)

This invention relates to new and useful improvements in building construction, and particularly to improvements in so-called prefabricated houses.

It is the object of the present invention to provide for an easily assembled prefabricated structure that will have great structural strength even without the customary frame work.

With this object in view I assemble a building of a number of relatively large and self-sustaining bodies or units, e. g., sheet steel cylinders which intersect and interlock with other similar bodies to form adjacent rooms, the enclosed overlapping areas automatically providing storage rooms, bath rooms, kitchens, and other service purposes.

The cylinders or other units may intersect either literally, by means of notching as hereinafter described, or virtually by reason of the continuation of the line of one perimeter through another perimeter which crosses such line.

If properly anchored and braced, such interlocking cylinders will constitute a strong and permanent structure, although none of the usual frame work is provided. The walls of such a structure serve not only for the purpose of enclosing the rooms and service areas, but to a great extent also for the purpose served in the customary building by the steel or wooden frame work.

Preferably though not necessarily each steel cylinder is placed within a second cylinder spaced and braced with respect to the first cylinder. The intervening space is filled with insulating materials or, under some conditions, the dead air between the cylinders may give sufficient insulation.

While the self-sustaining bodies have been referred to as cylinders made of sheet steel, they can also be made of other metals as well as other materials, e. g., compacted cellulose fibers, synthetic resins and of numerous other plastic substances, and their shape can be altered as desired. The steel cylinders or other units out of which the building is assembled are formed from flat sheets punched or stamped with all notches, window and door openings, service inlets, etc., the extreme ends of sheets being brought together and welded or otherwise securely fastened together.

From the standpoint of cheapness of construction, the ideal arrangement is to construct the self-sustaining room units, e. g., a cylinder, completely in the assembly plant, with doors and windows finished and even book shelves, closets, bathroom fixtures, kitchen and dining room equipment, etc., attached to the walls. Such completely prefabricated self-sustaining units can be quickly interlocked and anchored on the house site. How-

ever, owing to the size of the complete unit, it may be necessary to distort the cylinders into long ellipticals for shipment, restoring them to required shape at the site. Where a large number of houses are constructed in one closely knit development, a temporary assembly plant for such units could be set up in the neighborhood. Where this is not feasible, the units, with or without fixtures attached, could be manufactured in sections. For instance, a cylinder can be divided into two halves or four quarters and these then butt-welded or otherwise fastened together on the job into a complete cylinder. Similarly, flat sections can be assembled into square rooms. Obviously, sectional units could be completely prefabricated at the factory, even to most of the equipment, painting, finishing inside and out, etc.

In the drawings, Fig. 1 is a perspective view of one of the two principal units of my construction before assembly;

Fig. 1a is a perspective view of the other of the two principal units of my invention.

Fig. 2 is a top plan view of a three-unit assembly;

Fig. 3 is a vertical cross-section;

Fig. 4 is a horizontal cross-section illustrating the mounting of the units;

Fig. 5 is a vertical cross-section illustrating the roof structure;

Fig. 6 is a diagrammatic illustration of a typical layout;

Fig. 7 is a front elevation of a modified assembly;

Fig. 8 is a sectional view along line 8—8 of Fig. 7; and

Fig. 9 is a sectional view along line 9—9 of Fig. 7.

The principal unit of the construction shown in Figs. 1—6 consists of a self-sustaining body, such as an open-ended cylinder of sheet steel or other suitable material. The cylinder is provided with notches 2 and 3 extending from the top edge down to the midpoint of the cylinder. These notches 2 and 3 may be any distance apart, depending on the size and shape of the cooperating unit and the room layout desired. A second unit 4 is provided with notches 5 and 6 extending from its bottom edge up to the midpoint. The spacing between notches 5 and 6 will be the same as the spacing between notches 2 and 3.

Two such units may be assembled by lifting cylinder 4 above cylinder 2 so that notches 5 and 6 will register with notches 2 and 3, and then pushing the cylinder 4 down into the notches 2 and 3 until the top edges of the two cylinders are flush.

The two self-sustaining cylinders are now firmly interlocked.

Not only can the spacing between the notches of a cylinder be varied to meet specific requirements, but the length of the notches may also be varied. For instance, the notches in one cylinder may extend one-third the length of the cylinder, and the notches in the cooperating cylinder will then extend two-thirds the length of the cooperating cylinder but in the opposite direction.

A three-unit assembly is illustrated in Fig. 2. One of the units 7 is cylindrical and the other two 8 and 9 are rectangular. Obviously, any other shape may be adopted, and the reference in this specification to a "cylinder" is not intended to exclude other geometric forms. Each of the units 7, 8 and 9 consists of two concentric cylinders 10, 11, 12, 13, 14 and 15, interlocked as explained in connection with Fig. 1. The space between concentric cylinders like 10 and 11 may be filled with suitable insulating materials except where windows, doors, or other openings are cut in the walls. The spaces enclosed by interlocking bodies, i. e., 16, 17, may be used for service rooms, e. g., closets, bathrooms, kitchen, storage space, etc., and the balance of the space within each body is used as a room. A typical layout using four cylindrical units is shown in Fig. 6 which is self-explanatory.

Referring particularly to Figs. 2 and 3, I shall explain the manner in which steel cylinders like 10 and 11 are mounted and anchored.

19 are columns, and 20 is a concrete footing on which a number of steel rafters 21 of any suitable shape are set. The inside cylinder 11 is set within the notch 22, cut in the upstanding rib 23 of the rafter, the lower edge of the cylinder 11 being slotted at 24 to straddle the rib 23 between the bottom of notch 22, so that the cylinder will be seated on the rafter 21. Similarly, the outer cylinder is seated in a notch 25 provided in the rib 23, and its lower edge is slotted at 26 to straddle the unnotched portion of the rib.

The notch 22 is wide enough to receive a steel upright brace or studding 27, by means of which the inner and outer walls are spaced from one another and which cooperate in the bracing of the structure. It will be seen, therefore, that the rafters or joists on which the bodies are seated serve also to brace and interlock these bodies.

In addition to the cylinder 11 and the angle studding, the notch 22 encloses also a layer of expansion material 28 and a steel hoop 29 parallel with the inner cylinder 11. 28 and 29 extend all the way down to the joist, the lower end of 29 being slotted. Similar layers of expansion material 30 and a steel hoop 31 are provided in the notch 25 outside of the cylinder 12.

An expanded metal web 32 is placed over and fitted between rafters 21 and is covered with a layer of concrete 33 as is usual in floor construction. This layer of concrete, as well as flooring 34 placed on top of it, extends all the way to the steel hoop 29. Concrete is poured over the free end of the rafter 21 up to the steel hoop 31, as indicated at 35, with proper provision to prevent corrosion of the steel.

The expansion material 28 and 30 will guard against cracking of the flooring and the concrete which may be caused by changes in temperature and different expansion ratios of steel and concrete.

Where two steel rafters 21 intersect, they are interlocked by notching them in the same manner in which the room units are notched, i. e., a

slot such as 36 cut in the rafter, and extending from the top of the rib down to approximately the midpoint thereof, cooperates with a notch cut in the opposite direction through the head and bottom part of the rib of the intersecting rafter.

Wherever rafters, studding, room units, etc., intersect, they may be insulated from one another or welded to one another, depending on the specific requirements to be met.

The ceiling is substantially a duplicate of the flooring and is built on steel rafters 40 which contact with the tops of the upright studs or braces of the room units and brace and interlock them in the same manner as rafters 21. Sheets of steel or other roofing material 41 may be provided on top of the roof rafters or trusses, and sheet steel or other ceiling material may be attached on the bottom of the rafters to form a finished ceiling. Space between roof and ceiling sheets is utilized for insulation and conduits, electric wires, etc. The upper ends of the cylinders 11 and 12 are held between sheets of expansion material 42, 43 and steel hoops 44, 45. The latter is provided with a flange 46 interlocking with a sheet of steel 47 forming part of the roof proper.

In order to facilitate the transportation of the prefabricated sections of the structure and to permit the use of light gauge steel sheets, the construction illustrated in Figs. 7 to 9 may be adopted to make up parts or all of the structures illustrated in the other figures.

In accordance with this modification, the building is divided into panels or sections of various types and of widths, say 2, 3, 4 feet, or even wider. One panel 60 may contain a window 61 with frame prefabricated, another panel 62 may be prefabricated with a complete door 63, and a third type of panel 64 may be just a flat wall.

Each of these panels, as best shown in Figs. 8 and 9, consists of two sheet steel walls 65 and 66 parallel with one another and spaced as described in connection with the other figures to constitute outside and inside walls of the finished structure. The two sheets 65 and 66 are at their ends spot-welded to channel members 67, 68, extending throughout the height of the structure and lending the required rigidity thereto.

One section is held against the adjacent section by a bolt 69 projecting through the vertical channel 67 of one, and the corresponding channel 70 of the adjacent section. The bolt 69 is slotted at its end which projects from the channel 70, and a tapered pin 71 may be driven through the slot to hold the bolt 69 in place. The space between the channel members 67, 70 may be filled with a wood spacer block 72. The seams made by abutting ends of adjacent sections may be covered with a strip of steel or other suitable material 73, to provide a pleasing finish.

As in the previously described structures, the space between the parallel walls of the panels may be filled with insulating material and it may contain suitably fastened to the walls conduits 74, electrical cables 75, and the like. The sections can be fully assembled and partly or completely painted or decorated in the assembly plant, and other fixtures such as electric outlets 76, radiators 77, and the like, attached to the sections in the plant.

While in Figs. 7 to 9 I have illustrated flat sections suitable for making up rectangular rooms, it will be obvious from the foregoing that these sections may be curved and constructed to

make up rooms of any shape. For instance, if it is desired to make up rooms of circular cross-section, the walls and the stiffening channels will, of course, have to be fabricated to the required radius.

The side walls are set in an inverted channel 80 set in a hot bituminous layer in a groove of a concrete foundation 81. Horizontal rigidity is given to the structure by floor joists 82 clipped to the walls at the vertical channel members by suitable attaching means 83.

Roof girders 84 are notched as indicated at 85 to fit over inverted channel 87 covering the top of the wall, preferably at suitable intervals where they will engage the tops of vertical channels joining the wall panels. The girders 84 are also preferably provided in alignment with the vertical channel members and are fastened thereto by suitable means 86 projecting through the channel 87.

What is claimed is:

1. In a prefabricated building structure, a plurality of self-sustaining bodies having oppositely directed cooperating slots by means of which they are interlocked in partially overlapping relation, the main area within each body serving as a room and the overlapping areas of adjacent bodies as service rooms, and a plurality of rafters on which said bodies are seated and by which they are braced and interlocked.

2. In a prefabricated building structure, a plurality of self-sustaining cylinders having oppositely directed cooperating slots by means of which they are interlocked in partially overlapping relation, the main area within each cylinder serving as a room and the overlapping areas of adjacent cylinders as service rooms, and a plurality of rafters on which said cylinders are seated and by which they are braced and interlocked.

3. In a prefabricated building structure, a plurality of self-sustaining bodies open at their tops and bottoms, and having oppositely directed cooperating slots by means of which they are interlocked in partially overlapping relation, the main area within each body serving as a room and the overlapping areas of adjacent bodies as service rooms, and a plurality of rafters engaging the tops and bottoms of said bodies and by which they are braced and interlocked.

4. In a prefabricated building structure, a plurality of self-sustaining open-ended cylinders having oppositely directed cooperating slots by means of which they are interlocked in partially overlapping relation, the main area within each cylinder serving as a room and the overlapping areas of adjacent cylinders as service rooms, and

a plurality of rafters engaging the tops and bottoms of said cylinders and by which they are braced and interlocked.

5. In a prefabricated building structure, a plurality of self-sustaining bodies having oppositely directed cooperating slots by means of which they are interlocked in partially overlapping relation, the main area within each body serving as a room and the overlapping areas of adjacent bodies as service rooms, a second self-sustaining body concentric with each of said bodies, insulating material within the spaces between concentric bodies, and a plurality of rafters on which all said bodies are seated and by which they are braced and interlocked.

6. In a prefabricated building structure, a plurality of self-sustaining steel sheet cylinders open at both ends having oppositely directed cooperating slots by means of which they are interlocked in partially overlapping relation, the main area within each cylinder serving as a room and the overlapping areas of adjacent cylinders as service rooms, a second self-sustaining sheet steel cylinder concentric with each of said cylinders, insulating material within the spaces between concentric cylinders, and a plurality of rafters contacting with the top and bottom edges of said cylinders and by which they are braced and interlocked.

7. In a prefabricated building structure, a plurality of self-sustaining steel sheet cylinders having oppositely directed cooperating slots by means of which they are interlocked in partially overlapping relation, the main area within each cylinder serving as a room and the overlapping areas of adjacent cylinders as service rooms, a second cylinder concentric with each of said plurality of cylinders, insulation in the spaces between concentric cylinders, a plurality of T rafters on which said cylinders are seated with slots in the lower ends of the cylinders straddling the upstanding correspondingly slotted ribs of said rafters, the slots in said ribs straddling said cylinders, a layer of expansion material applied to the outside surfaces of the concentric cylinders at the bottoms thereof, a sheet of steel covering each sheet of expansion material, and flooring contacting with the last-mentioned sheets of steel.

8. In a prefabricated building structure, a plurality of self-sustaining bodies having oppositely directed cooperating slots by means of which they are interlocked in partially overlapping relation, the main area within each body serving as a room and the overlapping areas of adjacent bodies as service rooms.

EDWIN BIRD WILSON.
